CLAIM

The ornamental design for a combined bottle and cap, as shown and described.

DESCRIPTION

FIG. 1 is a side elevation of a combined bottle and cap showing my new design, the opposite side is a mirror
image thereof;

FIG. 2 is a front elevation thereof;

FIG. 3 is a top plan view thereof;

FIG. 4 is a side elevation of a second embodiment of the combined bottle and cap, the opposite side is a mirror
image thereof;

FIG. 5 is a front elevation of FIG. 4; and

FIG. 6 is a top plan view of FIG. 4.
